Filed Dec. 6, 1961, Ser. No. 67,822

Term of patent 14 years.

(Cl. D26—5)

FIG. 1

FIG. 2

FIG. 1 is a perspective view of the front and right hand side of a cabinet for a tape drive, showing our new design.

FIG. 2 is a perspective view of the top, rear and left hand side thereof.

The characteristic features of our design reside in the shadow box effect caused by square pillars framing the front of the machine and the ventilating panels at the top and bottom of the front and rear side panels.

We claim:

The ornamental design for a cabinet for a tape drive, substantially as shown and described.
